UNITED STATES PATENT OFFICE.

CHARLES C. JENNINGS, OF CHICAGO, ILLINOIS, ASSIGNOR TO CHARLES H. THOMPSON AND GEORGE A. SHELEY, OF DETROIT, MICHIGAN.

TELEPHONE SYSTEM.

SPECIFICATION forming part of Letters Patent No. 488,502, dated December 20, 1892.

Application filed October 23, 1888. Serial No. 288,917. (No model.)

To all whom it may concern:

Be it known that I, CHARLES C. JENNINGS, a resident of Chicago, in the county of Cook and State of Illinois, have invented certain 5 new and useful Improvements in Telephone Systems, of which the following is a specification.

This invention relates to improvements in telephone systems heretofore operated on a 10 ground circuit from a single line wire permanently grounded at each end through fixed telephones located at the ends thereof, each of which instruments is necessarily equipped with the usual battery and magneto signal 15 bells. In such prior systems also, the line wire has been strung on poles having no other function than that of supports for the wire in the manner usual in the stringing of telephone and electric wires.

20 The object of this invention is to have a number of successive stations connected by broken circuits between each of the stations closed through one station only, and including a telephone there-at, each of which circuits is adapted to be closed at any point between the stations, by a portable telephone unaccompanied by a battery, and all of which 25 circuits are adapted to be closed through the intermediate stations, and the telephones 30 thereat cut out, thus constituting a single broken circuit between the end stations, closed through only one of said stations. I attain this object by the devices illustrated in the accompanying drawings in which,—

35 Figure 1, is a diagram view representing two stations connected by a telephone system embodying my invention. Fig. 2, a face view of the portable telephone showing the front plate thereof removed for the purpose of exposing the interior construction thereof. Fig. 3, a central vertical section thereof. Fig. 4, a rear elevation of the same. Fig. 5, a detail view showing the manner of bringing the line wires close to the earth when strung upon 40 poles. Fig. 6, an enlarged view more clearly showing the construction and relative arrangement of the parts at one station.

45 A telephone system such as herein shown and described is equally well adapted for use 50 on rail-road lines stock ranches, mines, and similar places where it is desirable to have

frequent communication with a fixed station, by a person or persons moving along the line between stations, but for clearness of illustration, is hereinafter shown and described in 55 connection with a rail-road, and the line wires forming the circuits shown as constituting a portion of the usual and necessary rail-road fence inclosing the right-of-way of the road. The general plan of operation of this system 60 is to have each station connected by a double grounded circuit with the stations on each side of it, but only one of which circuits is closed through the station, the telephoning along the line between the various stations 65 being always done in the same direction; thus any operator from any point between stations 1, and 2, must telephone into station 1, or say westward, while any operator between stations 2, and 3, must telephone into station 2, 70 also westward, and between 3, and 4, back to station 3, likewise westward, and so on, or vice-versa, it being immaterial as the direction in which the telephoning is done, so long as all talk in the same direction, that is, all 75 east, west, north or south or in any other direction from any point of the line, according to the direction which preference or convenience may dictate. Hence between every two stations there is an independent talking or 80 telephone circuit, which however, is open or broken at one of the stations, but may be closed at any point between the stations, all the talking between these stations being necessarily into the one through which the circuit is closed; the other station, however, at which the circuit is broken, being talked into from the other side thereof, from any point between it and the next station on that side, over a circuit closed through the station, but 85 broken through the next station, which is in turn connected with another beyond that, in the same manner. But this system also contemplates the connection of any number of these independent sections into a single section 90 encompassing and passing uninterruptedly through all of the intermediate stations, and connecting the two end or "all night" stations by a double grounded circuit in the same manner as in the case of the independent 95 sections into either one of which "all night" stations the talking may be done from any 100

intermediate point, according to the direction in which the circuit is closed.

In carrying out my invention, I employ two line wires A, B, the former of which I will designate the telephone or secondary wire, and the latter the battery or primary wire, each of which extends from one station to another, for instance, from station C, to station D, at each of which each wire is connected with switch-boards E, and F, of any ordinary construction, with which switch-boards are also connected in the usual manner, line telephone and battery wires, A, and B, connecting station C, with the next station to the left, and similar wires A, and B, connecting the station D, with the next station to the right. With each of these switch-boards are also connected ordinary telephones G, H, by means of which the operator at the station is enabled to converse with the operator along the line between the stations, the said switch-board also having connection for the ground wires from each telephone, for both the primary and secondary circuits, as usual in this class of devices; in addition to which, there is also connected with the switch-boards, batteries I, J, designed to charge the battery line wires B, and B², after the manner and for the purpose hereinafter described, in the circuits of which are also included electro-magnetic signal bells K, L, which serve as a signal from the operator along the line between the stations, as described further on.

M, is a portable telephone, minus, or rather unaccompanied by a battery, constructed in any suitable manner, and having the usual induction coil N, platinum point, O, carbon button P, and receiver, Q, inclosed in a suitable casing and provided with the usual electric connections for the primary and secondary current, so that the instrument is adapted to both receive and transmit speech or signals, the casing being mounted upon a base board R, provided at the top and bottom thereof with opposing metallic hooks S S' electrically connected with the receiving and transmitting devices, which hooks are designed to engage the line telephone and battery, or primary and secondary wires A, B, respectively, thus closing the double circuit formed by these wires, through the portable telephone and thereby placing the operator in communication with either one of the stations C, or D, at which the circuit is closed through the telephone at that point.

In detail, the primary and secondary circuits through the portable telephone may be traced as follows,—beginning with the primary current from the battery I, following along the battery wire B leading therefrom, which constitutes the primary side of a metallic circuit, to the lower hooks S, thence through a short wire S², to one end of the primary wire of the induction coil N, the opposite end of which primary wire is connected by a wire N' with the platinum point o, while the opposing carbon button P is connected by

a wire P' with the metallic plate P², with which also connects the ground wire n for grounding the circuit after passing through and operating the transmitter, (that is, the platinum point and carbon button) in the usual manner. The secondary circuits, beginning with the induction coil, is grounded through the wire Q', with which connects one end of the secondary wire of said coil, and also the wire Q² leading to the receiver, through which the current passes, as usual, and thence out to the ground through a return wire Q³, plate P³, and ground wire n. The opposite end of the secondary wire of the induction coil connects, by a wire N², with the upper metallic hook S', and thence out over the line telephone wire A, to the telephone G, the talking or secondary circuit through which will now be described.

Bearing in mind that each independent circuit or section is always broken at one station, and closed at the other, in order that the talking from any point between stations must be done to the one through which the circuit is closed, I will now trace out the electric circuit between the stations C, D, assuming that the circuit is closed at the station C, and open at D; that is to say, the telephone and battery wires A, B, are dead at the switch-board F, and the circuit between them must be completed at some point between the stations.

Beginning with the telephone wire A, we find that on the switch-board E, it is plugged in at a, to connect with the telephone loop wire b, leading to the secondary wire of the induction coil in the telephone G, and thence to the receiver G' thereof after passing through which latter in the usual manner, the current comes out through the wire c, and is plugged in at d, to the ground e, while the circuit, as a whole, being technically known as "a talking circuit" or a secondary circuit between the portable telephone M and the fixed telephone G at the station,

It will of course be understood that the telephone G is of ordinary structure, not necessary to be either illustrated or described in detail herein, comprising the battery for operating the transmitter on a short primary circuit, which passes through the usual induction coil from which is derived the secondary current for operating the receiver in the usual manner, after passing through which it is grounded, as just described. The wire f is primarily employed as a safety wire for conducting off atmospheric electricity, as usual in this class of telephones. The "battery circuit" extends through the battery wire B, to the switch-board E, where it is plugged in at g, to the battery loop wire h, leading to the battery I, from which in turn extends a wire i, leading to a switch or shunt j, adapted to be alternately connected with the ground wire e, either by a direct wire k, or through the signal bell K, and wire l; the switch j, being also connected with the switch-board E, by

means of wire *m*, which latter, however, is dead at the said switch-board, except when it is desired to cut out the telephone *G*, and connect this station direct with the station to which the wires *A*, and *B*, lead. Thus it will be seen that both the telephone and battery circuits are grounded at one end only, and that all that is necessary is to close the circuit between these two wires to make a complete "talking circuit" which is done by hooking on the portable telephone, as hereinbefore described, but for greater effectiveness and security, I also provide the portable telephone with a ground connection through the wire *n*, by means of which the ground circuit through the transmitter and battery is perfected in the usual manner, although the grounding of both the telephone and battery wires at the station through which the circuit is closed, will be sufficient for all practical purposes. It will also be observed that the signaling to the operator at the station is automatic and accomplished merely by the hanging of the portable instrument upon the telephone and battery wires, for with the shunt or switch *j*, in the position shown in the drawings, when the circuit is completed on the line by the instrument, the current passes through the signal bell *K*, and causes it to ring continually until the attention of the operator at the station is attracted, and the shunt switched off to the direct ground wire *k*, when the bell stops ringing, after which the operator communicates with the operator on the line. The switch or shunt *j*, is also employed to render the circuit continuous through a station by being turned midway between and out of contact with both the bell and ground wire *k*, but plugged into the line battery wire *B*, leading to the next station to the left, as shown by the dotted line at *o*, the bell and ground wire being now dead, while the circuit continues out through the switch-board and onto the line battery wire. Thus any number of intermediate stations may be cut out, and at the same time two distant "all night" stations connected so that an operator from any point along the line may talk into one of them and be sure of receiving the desired information, for it will be understood that on rail-road lines certain stations at large towns and cities are kept open or have operators present all night, while smaller intermediate stations are closed at night and have no operator, hence the desirability of having a continuous circuit through such closed stations.

Another important feature of this invention is that the necessity for having the line wires frequently if not continuously near the earth, for convenience of attachment thereto of the portable telephone, enables the employment of the line wires as a substantial portion of the rail-road fence, necessary to inclose the right-of-way of the road, preferably forming the two upper wires of such a fence, which may as a whole, be composed of

three or five wires, according to choice or necessity, all but the two upper line wires of which are preferably barbed wire such as is 70 ordinarily used for such purposes, although, if desired, all of the wires might be of barbed wire. It will also be understood that each of the line wires, whether barbed or not, are insulated from the supporting posts, which are 75 also preferably metallic, and of any suitable construction, in any well known and convenient manner, such a fence combining strength and utility, besides being economical in construction by reason of the line wires constituting a material part thereof. But so far as relates to the broad idea of my invention, it is not necessary that the line wires should constitute a part of the rail-road or any other fence, for the same end would be attained by 80 conducting the wires underground through a suitable conduit and bringing them to or above the surface of the ground at short intervals, or by stringing them along on poles in the usual manner, and hanging them down 85 at suitable intervals to within easy reach of the operator as shown in Fig. 5, where they are strung across a board *p*, between posts *q*, *r*, for convenience of attachment of the portable telephone in the same manner as if the 90 wires were strung along on, and formed part of the fence as heretofore described. This latter method of stringing the line wires will be found of especial utility in swampy countries where the fence is not feasible or practicable, and in many other similar places such as long trestles, and marsh ground, or such a section may form only a portion of the entire line between two or more points.

The most important advantage derived 105 from such a system of telephoning as herein described, is that the operator along the line is relieved of the necessity of carrying the usual complete and heavy telephone, comprising a receiver, transmitter, magneto signal bells and a battery, the safe carriage of which latter is extremely difficult and irksome, and need only carry a light, compact and portable instrument comprising only a receiver and transmitter, which may almost 110 be carried in an ordinary coat pocket; beside which, the mere hanging of the instrument upon the wires closes the circuit, and automatically rings a signal bell until the 115 attention of the station operator is attracted. 120 Such an advantage is of incalculable value, in the case of workmen engaged along the line, or in case of an accident between stations, enabling immediate and rapid communication between such point and a station, without the 125 necessity for the service or presence of a skilled operator, as in the case of telegraphing, and at best is far quicker, and more convenient, even in the hands of a mere novice.

In conclusion I may state that should it be 130 found desirable to communicate with the nearest station, although the circuit is broken thereat, it is only necessary for the operator at the other station to communicate by the

- permanent telephone or telegraph connections between such points, with the operator at the desired station, and then shift the plugs in his switch-board so as to cut off or deaden the line wires at his station, while at the same time the operator at the other station plugs in the line wires, when the communication will be received into the desired station direct; but the simplest and most practicable manner of enabling communication in either direction from a given point would be to have two complete circuits one on each side of the road, (especially if they constitute a part of the rail-way fence,) working in opposite directions correspondingly with the directions in which the trains run, if on a double track-way, thus avoiding confusion and delay, and enabling workmen to talk into the nearest station from any point along the way.
- Having described my invention what I claim and desire to secure by Letters Patent is:—
1. In a telephone system the combination with a series of stations connected with each other by a series of broken double circuits, each of which is closed through one of the two stations connected thereby, a battery and fixed telephone at each of said stations, and

electro-magnetic bells included in the telephone loop circuit, of a portable telephone unaccompanied by a battery, adapted and arranged to close any one of said broken circuits at any point intermediate said stations, substantially as and for the purpose described.

2. In a telephone system, the combination with a series of stations, each of which is connected by a broken double circuit, with the stations on each side thereof, said circuits being closed through one of the stations only, with which it is connected, and having a telephone in the circuit at such station, of batteries, located at each of said stations, the loop circuit of each of which is adapted to be placed in circuit with the broken double circuit terminating at said station, whereby all the intermediate stations may be connected into a single broken circuit between the two stations, and a portable telephone unaccompanied by a battery, adapted and arranged to close said circuit, at any point between said end station, substantially as described.

CHARLES C. JENNINGS.
